(57) **CLAIM**

The ornamental design for a display panel with graphical user interface as shown and described.

DESCRIPTION

FIG. 1 is a front view of a first image of a display panel with graphical user interface showing our new design;

FIG. 2 is a second image thereof;

FIG. 3 is a third image thereof;

FIG. 4 is a fourth image thereof;

FIG. 5 is a fifth image thereof; and,

FIG. 6 is sixth image thereof.

The appearance of the image sequentially transitions between the images shown in FIGS. 1-6. The process or period in which one image transitions to another image forms no part of the claimed design. The outermost broken line rectangle shows a display panel, and forms no part of the claimed design.
